BOBBIN HOLDER

Joseph E. Leake, Fall River, Mass.

Application June 21, 1945, Serial No. 600,783

4 Claims. (Cl. 139—251)

1

This invention relates to means for holding the lowermost filling carrier or bobbin in a magazine loom, so as to prevent its rotation or oscillation prior to being transferred into the shuttle of the loom.

In magazine looms, filling carriers or bobbins are placed in a rotating battery or magazine and the ends from the carriers are wound around the axis on which the battery plates are mounted, so as to provide an end which can be used by the thread grippers for gripping the ends when the filling carrier is transferred into the shuttle upon the exhaustion of the filling on the preceding carrier.

It has been experienced, heretofore, that vibration in the loom causes rotation or oscillation of the lowermost filling carrier in the magazine loom prior to its transfer to the shuttle, and the end of the thread extending therefrom will become broken so that when the filling carrier is transferred into the shuttle, the end will not be engaged by the thread gripper and the loom will cease operating.

The primary object of this invention is to provide improved means for holding the lowermost filling carrier or bobbin in a magazine prior to its transfer into the shuttle of the loom, so that the filling carrier cannot oscillate or rotate prior to its transfer into the shuttle.

A further object of this invention is to provide an improved bobbin holder for normally engaging the lowermost filling carrier or bobbin in a loom magazine, said holder being carried by the transfer arm of the loom and being automatically operable thereby to disengage from said bobbin upon actuation of the transfer arm to transfer the filling carrier or bobbin into the shuttle.

Still further objects of the invention are to provide a bobbin holder which is of extremely simple and durable construction, which includes an efficient and readily renewable bobbin-engaging element, and which includes simple and efficient guiding and supporting means adapted to coact with a flange of the battery stand.

The exact nature of the present invention will become apparent from the following description when considered in connection with the accompanying drawings.

In the drawings—

Figure 1 is a transverse sectional view through the battery and lay of a magazine loom, showing the present invention applied thereto.

Figure 2 is a sectional plan view taken on line 2—2 of Figure 1, but showing the lay disposed in

2

a position for receiving a bobbin or filling carrier of the magazine.

Figure 3 is an elevation taken on line 3—3 of Figure 1.

Figure 4 is a central longitudinal sectional view of the holder per se, drawn on an enlarged scale and taken substantially on line 4—4 of Figure 1.

Figure 5 is a fragmentary rear elevational view showing an end portion of the holder illustrated in Figure 4.

Referring in detail to the drawings, the numeral 10 denotes a conventional battery stand for a battery loom, which has rotatably mounted

15 therein battery plates 11 and 12, which are spaced from each other for supporting the filling carriers 14. When a filling carrier 14 reaches its lowermost position, where it is to be transferred into the shuttle, there is a tendency for the filling carrier to oscillate or rotate, thereby breaking the end of the yarn and causing the loom to stop or a mis-pick to occur in the cloth which is being woven. It is necessary, therefore, to provide a holder which presses against the lowermost bobbin and prevents it from oscillating or rotating, due to vibration.

In order to accomplish this result, I have provided a bobbin holder 15 which has a resilient element 16 at one end for normally engaging the filling on the lowermost filling carrier 14. The other end of the holder 15 is pivoted upon the pin 17 which is rotatably mounted in the lower end of a leg 19 of the usual transfer member 20. The usual dog 21 is fixed on pin 17 and is adapted to be normally held in the full-line position of Figure 1.

The holder 15 includes an elongated bar provided, at its end remote from the filling contacting element 16, with an opening 22 receiving the pin 17 so as to be pivotally mounted on the latter, 40 a cotter pin 22 being used to retain the holder 15 on the pin 17. A torsion spring, considerably shorter than that commonly employed on the pin 17, may be interposed between the member 15 and the arm 19 to hold the dog 21 in its normal position, which spring is omitted for sake of clearness.

Intermediate its ends, the holder 15 is provided with an inward projection 23 in which are anchored two spaced, inwardly projecting guide pins 24. The stand 10 has a horizontal outwardly projecting flange at 25, and the pins 24 project above and beneath this flange 25 to guide the holder 15 when moved to bring the contact element 16 into or out of engagement with the filling on the lowermost bobbin 14. The uppermost one of the pins 24 rests upon the flange 25

45

50

55

Figure 2 is a sectional plan view taken on line 2—2 of Figure 1, but showing the lay disposed in

so as to effectively support the holder 15 in proper position. The filling contacting element 16 consists of a body of soft and highly resilient material such as sponge rubber, and one end of this body is compressed and forced through a restricted opening *a* of a laterally directed ear 26 provided on the end of holder 15 remote from that having the pivot opening 22. The natural expansion of this member 16 retains it in place, although it may be manually removed for renewal when necessary. It will be noted that the bobbin holder is of a unitary character and requires no separate guiding element. Also, the pins 24 may be readily disposed above and below the flange 25 when the holder 15 is placed on the pivot pin 17. The transfer member 20 has the usual laterally extending end 27 which is adapted to engage the filling carrier 14 when a transfer is made.

In the normal operation of the loom, lay 29 oscillates back and forth and the shuttle 30 simultaneously traverses the loom to cause the filling upon the filling carrier 14 to be placed in the warp. Upon exhausting of yarn upon the filling carrier 14 which is in the shuttle 30, suitable conventional mechanism will be thrown into operation to cause the dog 21 to move to the dotted line position of Figure 1. As the lay moves to the dotted line position of Figure 1, the bunter 31, which is secured to lay 29, will engage dog 21 to swing the transfer member 20 downwardly, which will cause the filling carried 14 to be transferred into the shuttle 30. It will also be noted that shortly prior to the transfer, the bobbin holder 15 will be withdrawn from the lowermost filling carrier simultaneously with the movement of arm 27, thereby allowing transfer arm 27 to transfer the lowermost bobbin without any obstruction. Immediately after the transfer, the battery plates 11 and 12 rotate until the next bobbin assumes the lowermost position previously occupied by the bobbin transferred, and the members will again assume their full line positions, at which time the bobbin support will be engaging the yarn on the lowermost bobbin. The transfer arm 20 is normally held in raised position, as shown by full lines in Figure 1, by means of a conventional torsion spring 32, which also holds member 15 against the yarn on the lowermost bobbin. The resilient element 16 is preferably constructed of special sponge rubber, is shaped so that it rests against the bobbin of filling with a very light pressure, and has a suction action. It is also self-adjusting, due to the high resilience of this type of rubber, thus compensating for the 55 different diameters of bobbins of filling.

From the foregoing description, it will be seen that I have provided a novel and efficient means for holding the lowermost bobbin in a magazine loom, said means being carried and operated by the transfer arm so that the bobbin holder will not interfere with the transfer operation. Minor changes may be made in details of construction illustrated and described, such as fall within the scope of the invention as claimed.

10 What I claim is:

1. In a loom having a battery stand provided with a horizontal flange and carrying a rotary battery for holding a plurality of filling carriers, and having a lay for confining a shuttle and having a transfer mechanism including a transfer arm for transferring the lowermost filling carrier from the battery to the shuttle upon exhaustion of the filling on the carrier in the shuttle, said transfer arm having a downwardly projecting arm, a bar having one end pivotally connected to the lower end of said downwardly projecting arm, and having a member on the other end thereof for engaging the filling on the lowermost filling carrier, and a pin fixed to said bar and slidably resting on said flange of the battery stand for slidably supporting said bar intermediate its ends.

20 2. The construction defined in claim 1, in combination with a second pin fixed to said bar, and 30 slidably disposed beneath said flange.

3. The construction defined in claim 1, wherein said bar has an inward enlarging intermediate its ends in which said pin is fixed.

4. The construction defined in claim 1, wherein 35 said bar has a laterally extending ear having an opening therein, and wherein the filling-engaging member comprises a body of soft, resilient material having one end highly compressed and disposed through the opening of said ear so as 40 to be retained in the latter by its own resiliency.
